UNITED STATES PATENT OFFICE

102,241

DESIGN FOR A TEXTILE FABRIC OR SIMILAR ARTICLE

Edward A. Smith, Haworth, N. J., assignor to
Collins & Aikman Corporation, Philadelphia,
Pa., a corporation of Delaware

Application June 11, 1936, Serial No. 63,223

Term of patent 14 years

To all whom it may concern:

Be it known that I, Edward A. Smith, a citizen of the United States, a resident of Haworth, in the county of Bergen and the State of New Jersey, have invented a new, original, and ornamental Design for Textile Fabrics or Similar Article, of which the following is a specification, reference being made to the accompanying drawing, forming part thereof.

The figure is a plan view of a piece of textile fabric showing my new design.

The design comprises a woven textile fabric having the diagonal blocks A and B which al-

ternate with one another to constitute the design repeat. The blocks A and B comprise light and heavier winding lines which cross each other to form different sizes and shapes of irregular blocks of the field color and small centrally located blocks of a contrasting color. The diagonal lines on the drawing denote the preferred position of application of the design when applied to upholstery.

I claim:

The ornamental design for a textile fabric or similar article as shown and described.

EDWARD A. SMITH.
